H. F. WINSLOW.
GRINDING MILL.
APPLICATION FILED JULY 24, 1920.

1,396,152.

Patented Nov. 8, 1921.

UNITED STATES PATENT OFFICE.

HARRY F. WINSLOW, OF BROOKLYN, NEW YORK.

GRINDING-MILL.

1,396,152.

Specification of Letters Patent.

Patented Nov. 8, 1921.

Application filed July 24, 1920. Serial No. 398,703.

To all whom it may concern:

Be it known that I, HARRY F. WINSLOW, a citizen of the United States, and resident of Brooklyn, in the county of Kings and 5 State of New York, have invented certain new and useful Improvements in Grinding-Mills, of which the following is a specification.

This invention relates to an attachment 10 for grinding mills of the type adapted for use in grinding viscous materials such as paints, inks, chocolates or the like, the invention having particular reference to the distribution of the material on the surface 15 of the grinding rolls.

Grinding mills of this type ordinarily comprise a succession of grinding rolls over which the material is carried, being drawn from one roll to the next succeeding one. In 20 the ordinary operation of these mills the coarser particles of the material have a tendency to gradually work outwardly from the center to the opposite ends of the rolls, necessitating the removal or stripping of the 25 material on the end portions of one of the later rolls of the sequence and the refeeding of such material to the mill, this refeeding being commonly done by hand.

The present invention has for an object to 30 automatically effect the collection of the coarser particles from the ends of the later roll and refeed the same to an earlier roll, while leaving the finely ground particles at the center of the roll to pass on to the dis- 35 charge point.

More specifically, the invention has for an object to provide a simple and inexpensive device for the above purpose which may be easily attached to the ordinary form of mill. 40 For further comprehension of the invention, and of the objects and advantages thereof, reference will be had to the following description and accompanying drawings, and to the appended claims in which 45 the various novel features of the invention are more particularly set forth.

Figure 1 of the drawings is a longitudinal vertical sectional view of a grinding mill provided with my improved attachment, this 50 view being taken on the line 1—1 of Fig. 2.

Fig. 2 is a plan view of the mill.

Fig. 3 is a detail face view of one of the refeeding devices.

Fig. 4 is a transverse section on the line 4—4 of Fig. 3.

In the drawings I have illustrated my attachment applied to an ordinary mill comprising the three grinding rolls, 1, 2 and 3 suitably journaled in side frames 4. The roll 1 may be rotated by a suitable belt applied to a pulley 5 on one end of the roll shaft 1'. This roll imparts rotation at an increased rate of speed to the second roll 2 by means of a gear 6 on the other end of its shaft 1' which meshes with a smaller gear 65 7 on the end of the shaft 2' of the second roll 2. The third roll 3 is rotated at a still further increased speed by another gear 8 on the shaft 2' which meshes with a smaller gear 9 on the shaft 3' of the third roll. These 70 parts as just described are of well known construction, the material to be ground being piled upon converging portions of the rolls 1 and 2 as indicated at 10. A pair of vertical plates 11 are located between the converging portions of the rolls 1 and 2 adjacent the ends thereof to retain the material on the rolls, these plates being here shown as fixed on the ends of pins 12 secured in apertured members on the side frames 4 by screws 14. 80 A scraper 15 engages the roll 3 and removes the ground material which passes into a receptacle 16.

As here embodied my improved attachment comprises a pair of separated devices 85 located above the meeting line of the rolls 2 and 3 toward opposite ends thereof. Each of these devices comprises a housing 18 which is of inverted U-shape as seen transversely of the mill and having the legs 90 thereof, as viewed longitudinally of the mill, concavely curved on opposite sides as at 19 to fit the peripheries of the rolls 2 and 3, these two curved sides merging into a sharp point at the bottom so as to extend substantially down to the meeting line of the rolls. To retain these housings in position a pair of rods 20 are mounted in suitable eyes 21 on the side frames 4 in which they are detachably secured by set screws 22, these rods 100 having sleeves 23 slidable thereon and secured thereto by set screws 24. Each of these sleeves 23 has projecting rigidly downward therefrom a screw 25 which passes freely through an aperture 26 in the top of 105 the housing 18, this screw having a nut 27

threaded thereon and adapted to bear downwardly on the top of the housing to force the curved sides of the latter with a desired degree of pressure against the rolls 2 and 3.

5 Carried within each of the housings 18 is a scraper plate 30 which extends substantially the full interior area thereof and is preferably pivotally mounted therein, being here shown as provided with hinge brackets 31 which engage a rod 32 extending between and supported by opposite sides or legs of the housings. To permit of vertical adjustment of the scraper 30 the hinge brackets 31 are secured to the latter by headed screws 33 which pass through vertical slots 34 in the scraper and are threaded into the hinge brackets.

10 The scraper plate is positioned with the bottom, or scraping, edge thereof a short distance above the meeting line of the rolls, which are moving upwardly at their adjacent sides toward the scraper as indicated by the arrows. This bottom edge of the scraper is yieldingly pressed against the 15 rolls by a pair of expansion springs, such as 35, which are coiled around a pair of headed screw rods 36 passing freely through, and supported by, projections 37 on the housings, these rods having nuts 38 threaded 20 on their other ends, the springs 35 bearing between these nuts and the top of the scraper. To facilitate adjustment of the nuts on the rods the nuts are held against 25 turning movement, while the screw rods 36 are rotatable, the nuts having pins 40 projecting therefrom into grooves such as 41 in the sides of the housings 18. To permit 30 of the vertical adjustment, above referred to, of the scraper, the top of the latter is 35 vertically slotted toward opposite sides as at 42 to accommodate the rods 36 and has a central slot 43 to accommodate the screw 40.

40 In the operation of the mill with my improved attachment thereon the coarser particles of material which have worked toward the ends of the rolls are removed from roll 3 by the scraper 30 and thrown back on roll 2 and carried by the latter back to the feed point, while the finer ground material at the 45 center passes on to the receptacle 16. It will be noted that the sides of the housing act to retain this material against lateral movement which would tend to throw it off the ends of the rolls.

50 Having thus described my invention what I claim as new and desire to protect by Letters Patent of the United States is as follows:—

55 1. In a grinding mill comprising a series 60 of rolls adapted to operate in sequence upon the material and including a delivery roll for the finished product, a pair of devices spaced apart from one another longitudinally of said delivery roll and including 65 scrapers disposed substantially parallel to

the axis thereof, the said scrapers being adapted to collect the material from the end portions of said delivery roll for refeeding to the adjacent earlier roll of the sequence.

2. In a grinding mill comprising a series 70 of rolls adapted to operate in sequence upon the material and including a delivery roll for the finished product, a pair of separated scrapers arranged adjacent the surface of said delivery roll toward opposite ends 75 thereof, said scrapers being disposed substantially parallel to the axis of said delivery roll and adapted to remove the material from the end portions thereof and direct it upon the adjacent earlier roll of the 80 series.

3. In a grinding mill comprising a series 85 of rolls adapted to operate in sequence upon the material and including a delivery roll for the finished product, a pair of separated scrapers arranged adjacent the surface of said delivery roll toward opposite ends thereof, said scrapers being disposed substantially parallel to the axis of said delivery roll and adapted to remove the material from the end 90 portions thereof and direct it upon the adjacent earlier roll of the sequence, and means adjacent said scrapers preventing movement of the material toward the ends of the roll.

4. In a grinding mill comprising a series 95 of rolls adapted to operate in sequence upon the material and including a delivery roll for the finished product, a pair of separated scrapers arranged adjacent said delivery roll toward opposite ends thereof, said scrapers 100 having their scraping edges adjacent the meeting line of said delivery roll with the adjacent earlier roll of the sequence.

5. In a grinding mill comprising a series 105 of rolls adapted to operate in sequence upon the material and including a delivery roll for the finished product, a pair of separated scrapers arranged adjacent said delivery roll toward opposite ends thereof, said scrapers having their scraping edges adjacent the 110 meeting line of said delivery roll with the adjacent earlier roll of the sequence, and comprising plate-like knives arranged substantially tangential to the said delivery roll.

6. In a grinding mill comprising a series 115 of rolls adapted to operate in sequence upon the material, a pair of separated scrapers arranged adjacent a later roll of the sequence toward opposite ends thereof said scrapers having their scraping edges adjacent the 120 meeting line of the said roll with the adjacent earlier roll of the sequence, and comprising plate-like knives arranged substantially tangential to the said roll, and means for yieldingly pressing said scrapers against 125 said roll.

7. An attachment for a grinding mill comprising a U-shaped housing having its sides concavely shaped to fit the converging portions of the peripheries of a pair of rolls, and 130

- a scraper carried wholly within said housing and adapted to engage one of said rolls adjacent to and parallel with the meeting line of said rolls and direct the material to be ground to the opposite roll.
8. An attachment for a grinding mill comprising a U-shaped housing having its sides concavely shaped to fit the converging portions of the peripheries of a pair of rolls, and a scraper carried in said housing and adapted to engage one of said rolls, and resilient means pressing said scraper against the said roll.
9. An attachment for a grinding mill comprising a U-shaped housing shaped to fit the converging portions of the peripheries of a pair of rolls, means for causing said housings to press against said rolls, and a scraper carried wholly within said housing and adapted to engage one of said rolls and direct the material to be ground to the opposite roll, said scraper being disposed parallel with and adjacent the meeting line of said rolls.
10. An attachment for a grinding mill comprising a U-shaped housing shaped to fit the converging portions of the peripheries of a pair of rolls, a scraper carried in said housing and adapted to engage one of said rolls, and means for causing said concaved sides of said housing to press against said rolls, said means including a fixed screw passing freely through an aperture in said housing, and a nut threaded on said screw and bearing on said housing.
11. An attachment for a grinding mill comprising a scraper, a support in which said scraper is pivotally mounted, a pair of screw-rods swiveled in said support, nuts threaded on said rods, and springs coiled around said rods and bearing between the latter and the scraper.
12. An attachment for a grinding mill comprising a scraper, a support in which said scraper is pivotally mounted, a pair of screw-rods swiveled in said support, nuts threaded on said rods, and springs coiled around said rods and bearing between the latter and the scraper, said nuts having projections engaging in slots in the said support, for the purpose set forth.
13. In a grinding mill comprising a series of rolls adapted to operate in sequence upon the material and including a delivery roll for the finished product, a scraper arranged adjacent said delivery roll toward an end thereof, said scraper being disposed substantially parallel to the axis of said delivery roll and adapted to remove the material from the end thereof and direct it upon the adjacent earlier roll of the sequence.
14. In a grinding mill comprising a series of rolls adapted to operate in sequence upon the material and including a delivery roll for the finished product, a scraper arranged adjacent said delivery roll toward an end thereof, said scraper being disposed substantially parallel to the axis of said delivery roll and adapted to remove the material from the end thereof and direct it upon the adjacent earlier roll of the sequence, and guiding means for the material co-acting with said scraper.

Signed at Brooklyn, in the county of Kings and State of New York, this 21st day of July, A. D. 1920.

HARRY F. WINSLOW.
